LEO ROSEMAN, OF NEWARK, NEW JERSEY.

FEMALE FASTENER MEANS FOR GARMENTS.

Application filed June 11, 1927. Serial No. 198,052.

This invention relates to improvements in fastener means for garments, and more especially to a novel form of female fastener means adapted for engagement by hook fasteners such as are commonly employed in connection with women's garments.

The present invention has for its principal object to provide a novel form of female or hook engageable fastener means in which enclosed and concealed metallic eye-members are employed in connection with a pocket-forming fold or strip associated with a garment edge opening, either in the form of a preformed separate fastener tape or as an integral part of the garment body itself; the present invention providing a further developed specific construction of female fastener means of the general character disclosed in my copending applications for Letters Patent Ser. No. 156,474, filed December 22, 1926 and Ser. No. 183,297, filed April 13, 1927.

Other objects of the present invention, not at this time more particularly enumerated, will be clearly understood from the following detailed description of the same.

The invention is clearly illustrated in the accompanying drawings, in which:—

Figure 1 is a fragmentary face view of the meeting portions of a garment equipped with the novel female or hook engageable fastener means of the instant invention; and Figure 2 is an enlarged sectional view of the same, taken on line 2—2 in said Figure 1.

Figure 3 is a fragmentary sectional view of the novel garment fastener means produced as an integral part of an edge of the garment body.

Figure 4 is an enlarged face view of the novel fastener means in tape form as applied to the margin of a garment opening, said view showing certain modifications hereinafter referred to.

Figure 5 is an enlarged face view of the novel fastener means constructed to provide for the selective adjustable reception of hook fastener for either comparatively loose or tight fitting of a garment upon the wearer's person.

Similar characters of reference are employed in all of the hereinabove described views, to indicate corresponding parts.

Referring to Figures 1 and 2 of the drawings, the novel female fastener means of the

instant invention is shown in the form of a 55 tape comprising a main body 1 having a folded rearward edge 2. The opposite or outer marginal portion of said tape body is folded over upon the face of the latter to provide a pocket-forming strip or section 3, 60 and the free edge portion 4 of such strip or section may be folded inwardly beneath the latter, if desired.

Arranged to underlie said pocket-forming strip or section 3, at spaced longitudinal intervals along the tape body, are metallic fastener elements. Said fastener elements preferably comprise a substantially rectangular formation of metallic wire to provide a forward side bar 5, a rearward side bar 6 65 and interconnecting end bars 7. Said fastener elements are thus enclosed and concealed between the tape body 1 and pocket-forming strip or section 3, and when the latter is provided with inwardly underfolded 70 edge portion 4, are preferably disposed intermediate such parts with the rearward side bar 6 lying in the juncture thereof.

To secure the parts in the above described assembled relation, fastening stitching is 80 sewn through the pocket-forming strip and tape body adjacent to the rearward edge of the former, and so as to traverse the fastener elements. Said fastening stitching may be variously formed. As shown in Figure 1 85 one form of such fastening stitching comprises a line of running stitches 8 extending between and traversing the end bars 7 of said fastener elements, the same being interrupted adjacent to the inner side of each 90 bar 7 by the formation of groups of transverse anchor stitches 9 which extend rearwardly across the rearward side bars 6 of the fastener elements and the rearward edge of the pocket-forming strip or section 3, thus 95 firmly and securely anchoring the fastener elements against displacement, either longitudinally or laterally. The thus formed stitching not only secures the fastener elements in place, but also stitches down the 100 rearward edge of the pocket-forming strip or section to the tape body.

The pocket-forming strip or section 3, as well as the underfolded portion 4 thereof, if the latter is employed, is provided with 105 openings or cutaway portions 10 bordering the inner side of the forward side bar 5 of each fastener element, and leading into the

interior pocket or space 11 provided intermediate the tape body 1 and said pocket forming strip or section 3.

The tape constructed as above described, 5 may be sewn by suitable connecting stitching 12 to an opening bounding marginal portion 13 of a garment, as shown in Figures 1 and 2. When thus operatively related to a garment the novel fastener tape is adapted to 10 cooperate with hook-fasteners 14, which are suitably associated with the opposite opening bounding marginal portion 15 of a garment. To close a garment opening thus equipped, the bills of the hook-fasteners 14 15 are entered through the openings 10 to hook around the forward side bar 5 of the fastener elements, said bills thus entering the interior pocket or space 11 provided intermediate the tape body 1 and said pocket-forming strip or section 3. The female fastener elements being strongly anchored by the stitching 8 and 9 carry the strain of the garment closure, as will be clearly evident. It will be obvious that when the garment is 20 closed, all metallic parts are covered and concealed, and that the garment, when worn next to the skin has no exposed metal which can contact with the latter. In addition to this advantage, the female fastener means 25 of this invention is of very neat appearance; the openings 10 afford an easy means for locating the fasteners, both by sight or by sense of touch alone, and the fastener means is exceedingly strong and durable, 30 all of which features are particularly desirable in connection with women's garments.

Again referring to Figures 1 and 2 of the drawings, it will be noted that provision of additional fastening stitching in connection with the fastener elements may be provided, the same consisting in a line of running stitches 16 extending only through the pocket-forming strip or section 3 and its underlying fold 4 when the latter is employed; said line of running stitches 16 passes adjacent to the outer side of the forward side bars 5 of the fastener elements, the same being interrupted by the formation of groups of cross stitches 17 which extend 50 rearwardly across the side bars 5 adjacent to the inner side of each end bar 7 of the fastener devices. The said stitching 16-17, as it does not extend through the underlying main body 1 of the tape, does not obstruct the interior pocket or space 11 of the tape. It will be obvious that said stitching 16-17 is made before the pocket-forming strip or section is turned over upon the face of the tape. It must be understood that the 55 use of said additional stitching 16-17 is entirely optional, and may be omitted if desired.

Referring now to Figure 3 of the drawing, I have shown the novel female fastener means embodying the principles of this in-

vention arranged to form an integral part of a garment body edge. In such arrangement the garment body 18 has its free marginal edge-portion folded rearwardly over upon its face to provide a pocket forming 70 strip or section 19 integral therewith, and the fastener elements 20 are arranged and secured by stitching in the same manner as above described in connection with the fastener tape arrangement. The pocket-forming strip or section 19 is provided with the openings or perforations 10' bordering the inner sides of the forward side bars of the fastener elements 20, and leading into the pocket space 21 provided between said 80 pocket-forming strip and the underlying garment body.

Referring now to Figure 4 of the drawings, I have shown therein a fastener tape corresponding to that shown in Figures 1 and 2 (as indicated by the application in said Figure 4 of corresponding reference characters), except that a modified arrangement of the main fastening stitching is shown. Said modified arrangement of main fastening stitching comprises a line of running stitches 8' extending between and traversing the end bars 7 of said fastener elements, the same being interrupted adjacent to the outer side of each end bar 7 by the formation of groups of transverse anchor stitches 9' and adjacent to the inner side of each end bar 7 by the formation of similar groups of transverse anchor stitches 9'', said groups of anchor stitches 9' and 9'' extending rearwardly across the rearward edge of the pocket-forming strip or section 3 and through the main body of the tape. This modified arrangement of fastening stitching is calculated to additionally reinforce 105 the attachment of the rearward edge of pocket-forming strip or section 3 to the tape body 1, as well as to additionally secure the fastener elements against displacement. It will also be noted that in said Figure 4 I have shown another way of applying the novel fastener tape to the marginal portion of a garment 22, by registering the tape over such marginal portion and then securing the same by stitching both longitudinal edges of the tape to the latter, as at 23 and 24. It will be understood that there are many other ways of applying the novel fastener tape to the garment body, and consequently the showing and description in this respect is to 110 be deemed merely illustrative and not in a limiting sense.

Referring now to Figure 5 of the drawings, I have shown a construction of fastener tape in which provision is made for 115 the selective use of either the forward or the rearward side bars of the fastener elements to receive engagement of hook fasteners, so that either a tight fitting or a comparatively loose fitting closure of a garment furnished 120

with the novel fastener means may be obtained. As will be obvious the fastener means constructed to so function may be made either in tape form or as an integral part of the garment edge portion. When made in tape form, as illustrated in Figure 4, the same comprises a main tape body 25 having a folded rearward edge 26, and pocket forming strip or section 27 with underfold free edge portion 28, said pocket forming strip or section being folded rearwardly over and upon the tape body. Arranged to underlie said pocket-forming strip or section, at spaced longitudinal intervals, are the metallic fastener elements comprising a substantially rectangular formation of metallic wire to provide a forward side bar 5', a rearward side bar 6' and interconnecting end bars 7', disposed in the fold intermediate the pocket-forming strip or section 27 and its underfolded portion 28. Fastening stitching comprising a line of running stitches 29 is sewn through the pocket-forming strip or section 27 and underlying tape body 25, the same traversing the end bars 7' of the fastener elements, but being interrupted at the inner sides of the latter by the formation of groups of transverse anchor stitches 30, extending across the rearward side bars 6' of the fastener elements and across the rearward edge of the pocket-forming strip or section 27 to pass through the tape body 25 beyond the latter. Interconnecting running stitches 31 extend between said groups of anchor stitches 30 beyond the edge of said pocket-forming strip or section 27, thus leaving said latter part unattached to the main tape body at points intermediate said anchor stitches and coincident to said rearward side bar, whereby an open hook receiving pocket 32 enters beneath the edge of said pocket-forming strip or section, the lip of which is bounded by said rearward side bar 6'. The body of the pocket-forming strip or section 27, as well as the underfolded portion 28 thereof, is provided with openings or cutaway portions 10" bordering the inner side of the forward side bar 5' of each fastener element, and leading into the interior pocket or space provided intermediate the tape-body and pocket-forming strip or section, in the same manner as above described. It will be evident that this modified arrangement of fastener means permits of a hook-fastener to be selectively engaged with either the side bar 5' or side bar 6' at will, and since these bars are laterally spaced, it will be evident that when the rearward side bars 6' are engaged by the hook-fasteners a relatively tight fitting closure of the garment will be attained as compared with the fitting obtained when engaging the hook-fasteners with the forward side bars 5' of the fastener elements. If desired, when providing this modified form of fastener tape, the rearward edge of the pocket-forming strip or section 27 may be cut away, as at 33, to expose the rearward side bars 6' to view, if so desired. It will be apparent that additional fastener element securing stitching comprising the running stitches 16' and cross stitches 17', similar to that already above described, may be employed in connection with the last described modified form of double female fastener means.

Having thus described the present invention, I claim:—

1. A garment fastener means separably engageable by hook-fasteners, comprising a base, a strip overlying said base to provide an intermediate pocket space, the rearward marginal portion of said strip being folded beneath the same; substantially rectangular metallic fastener elements comprising a forward side bar, a rearward side bar and connecting end bars; said fastener elements being disposed beneath and within the fold of said strip with their forward side bars positioned parallel to and intermediate the forward and rearward boundaries of said strip; said strip having a hook-entrance opening behind each forward side bar and leading into said pocket space; and means for securing said strip and associated fastener elements to said base. 80
2. A garment fastener means as defined in claim 1 in which the means for securing said strip and associated fastener elements to said base comprises stitching, including running stitches sewn longitudinally through said strips and base so as to traverse the end bars of said fastener elements, with transverse anchor stitches within and adjacent to the end bars and adapted to traverse the rearward side bars of said fastener elements. 90
3. A garment fastener means as defined in claim 1 in which the means for securing said strip and associated fastener elements to said base comprises stitching, including running stitches sewn longitudinally through said strips and base so as to traverse the end bars of said fastener elements, with transverse anchor stitches within and adjacent to the end bars and adapted to traverse the rearward side bars of said fastener elements, and further including an additional longitudinal line of running stitches sewn only through said strip, with cross stitches within and adjacent to the end bars and adapted to traverse the forward side bars of said fastener elements. 100
4. A garment fastener means separably engageable by hook-fasteners, comprising a base, a strip overlying said base to provide an intermediate pocket space; substantially rectangular metallic fastener elements comprising a forward side bar, a rearward side bar and connecting end bars; said fastener elements being disposed beneath said strip; 110

said strip having a hook entrance opening behind each forward side bar and leading into said pocket space; said strip further having hook-entrance openings also leading into said pocket space beneath the rearward edge thereof and coincident with the rearward side bars of said fastener elements;

and means for securing said strip and associated fastener elements to said base.

In testimony that I claim the invention 10 set forth above I have hereunto set my hand this 8th day of June, 1927.

LEO ROSEMAN.
